UNITED STATES PATENT OFFICE.

AUGUSTUS M. RYAN, OF ABILENE, TEXAS.

MAIL-BAG CATCHER.

1,288,210.

Specification of Letters Patent. Patented Dec. 17, 1918.

Application filed February 8, 1918. Serial No. 216,060.

To all whom it may concern:

Be it known that I, AUGUSTUS M. RYAN, a citizen of the United States, residing at Abilene, in the county of Taylor and State 5 of Texas, have invented new and useful Improvements in Mail-Bag Catchers, of which the following is a specification.

This invention relates to improvements in devices for receiving mail bags from moving trains.

In carrying out the present invention, it is my purpose to provide a device of the class described which may be set to receive mail bags from trains moving in either 15 direction, which will securely hold the bag when the same is delivered thereto by the train, and which will be constructed in such manner as to reduce the impact between the same and the bag, thereby preventing 20 mutilation of the bag and unnecessary jarring of the component parts of the apparatus.

It is also my purpose to provide a mail bag receiving apparatus which will embrace 25 the desired features of simplicity, efficiency and durability, which will operate effectively under all conditions and wherein the component parts will be so arranged and correlated as to reduce the possibility of derangement to a minimum.

With the above recited objects in view and others of a similar nature, the invention consists in the construction, combination and arrangement of parts set forth in 35 and falling within the scope of the appended claims.

In the accompanying drawings:

Figure 1 is a top plan view of a mail bag receiving apparatus constructed in accordance 40 with my present invention, the same being shown as receiving a mail bag from a train.

Fig. 2 is a view in side elevation of the train.

Fig. 3 is a vertical sectional view through the apparatus.

Fig. 4 is a horizontal sectional view therethrough, showing the parts in open position.

Fig. 5 is a similar view showing the parts 50 in closed position.

Referring now to the drawings in detail, 1 designates a track-way while 2 indicates a mail car adapted to traverse the track-way 1 and equipped with a mail bag delivery arm, as usual.

Arranged upon one side of the track-way

1 is a standard 3 suitably braced and, in the present instance, circumferentially reduced as at 4 adjacent to its upper end to form shoulders 5—5 appropriately spaced 60 apart. Mounted upon the circumferentially reduced portion 4 of the standard 3 and capable of rotary movement thereon is a sleeve 6 held against longitudinal movement with the shoulders 5—5 and secured to 65 the sleeve 6 in some suitable manner and projected outwardly therefrom are horizontal arms 7—7 spaced apart in parallelism. Secured to the arms 7—7 respectively adjacent the outer ends thereof are 70 axially alining trunnions 8 and rotatably mounted upon the respective trunnions 8 are plates 9—9. The lower plate is circular in shape while the upper plate is in the form of a segment and connecting the plates 9—9 75 is a vertical segmental web 10 secured to the plates adjacent the peripheries thereof and acting to hold such plates properly spaced apart. Arranged between the plates 9—9 and arranged diametrically opposite 80 each other are vertical pivot posts 11, spaced apart equal distances from the respective ends of the web 10. 12—12 designates semi-circular plates arranged between the plates 9—9 and pivoted upon the posts 11 85 respectively. When the plates 12—12 are swung in one direction, the inner ends thereof, that is, the ends adjacent to the web 10 overlap each other while the remaining ends are spaced apart to form an 90 entrance to the space between the plates as clearly illustrated in Fig. 4 of the drawings, while when the plates are swung in the opposite direction, as shown in Fig. 5, the outer ends thereof overlap each other while 95 the inner ends are spaced apart, the space between the inner ends of the plates being closed by the web 10.

In the present instance, coiled retractile springs 13 are mounted upon the opposite 100 sides of one of the arms 7 and each has one end fastened to the standard 3 and the remaining end secured to the adjacent side of the arm at the outer extremity thereof, such spring acting to hold the arms in normal position and to restore the same to such position succeeding the swinging thereof in one direction or the other. 14—14 designates trip arms secured to the upper end of the standard 3 and projecting outwardly 105 from the same above the arms 7—7 and adapted to release the mail bag from the

delivery arm on the car as the latter passes the receiving apparatus.

In practice, when it is desired to set the receiving apparatus to receive a mail bag from a passing car, the receiver, composed of the plates 9—9, the web 10 and the plates 12—12, is swung to such a position that the outer ends of the plates 12 will face the approaching car. The plates 12 are now swung about the respective pivot posts 11 to separate the outer ends of such plates so that the mail bag carried by the delivery arm on the car may pass into the space between the plates as the car passes the receiving apparatus. As the bag enters the space between the plates 12 the trip arms 14 release the bag from the delivery arm on the car and the bag strikes the inner ends of the plates 12, thereby swinging the latter about the pivot posts 11 to incase the bag and hold the same within the receiver. The arms 7—7 swing against the action of one of the springs 13 when the bag is delivered to the receiver so as to reduce the force of the impact between the bag and the receiver thereby preventing mutilation of the bag and unnecessary vibration of the receiving apparatus.

Formed on the lower plate 9 at diametrically opposite points and projecting outwardly therefrom are stop arms 15—15 adapted to engage the lower arm 7 to limit the turning movement of the receiver in one direction or the other.

While I have herein shown and described one preferred form of my invention, by way of illustration, I wish it to be understood that I do not confine myself to the precise details of construction herein described and delineated, as modification and variation may be made within the scope of the claims and without departing from the spirit of the invention.

I claim:

1. Mail bag receiving apparatus comprising a standard arranged adjacent to the track-way, a sleeve loosely surrounding said standard adjacent to the upper end thereof, arms secured to said sleeve and projecting outwardly therefrom and spaced apart, a receiver mounted between the outer ends

of said arms, and capable of rotation therein and embodying top and bottom plates spaced apart, pivot posts disposed between said plates and diametrically opposed and curved plates pivoted upon said posts respectively and adapted for swinging movement to throw the inner ends together and separate the outer ends whereby the bag may be delivered to the space between the plates and impact against the inner ends of the plates to close the latter around the bags.

2. Mail bag receiving apparatus comprising a standard arranged adjacent to the track-way, a sleeve loosely surrounding said standard adjacent to the upper end thereof, arms secured to said sleeve and projecting between the outer ends of said arms, and capable of rotation therein and embodying top and bottom plates spaced apart, pivot posts disposed between said plates, diametrically opposed and curved plates pivoted upon said posts respectively and adapted for swinging movement to throw the inner ends together and separate the outer ends whereby the bag may be delivered to the space between the plates and impact against the inner ends of the plates to close the latter around the bags, and resilient means holding said arms in normal position and adapted to yield under the impact of the bag on said plates.

3. In mail bag catching apparatus, a receiver adapted to receive the bag from the car comprising plates spaced apart vertically, diametrically opposed pivot posts between said plates, curved plates pivoted upon said posts respectively and capable of swinging movement thereon to draw the inner ends together and separate the outer ends whereby the mail bag may enter the space between the plates and impact against the inner ends of the plates to close the second mentioned plates around the bag, means supporting said receiver and a web positioned between the spaced plates to provide a stop for the pivoted curved plates and to form a continuation of the wall of the receiver.

In testimony whereof I affix my signature.

AUGUSTUS M. RYAN.
